UNITED STATES PATENT OFFICE.

THEODOR HOERMANN, OF BROOKLYN, NEW YORK.

DESIGN FOR A FRAME FOR BICYCLE PACKAGE-CARRIERS.

SPECIFICATION forming part of Design No. 25,619, dated June 9, 1896.

Application filed April 3, 1896. Serial No. 586,129. Term of patent 14 years.

To all whom it may concern:

Be it known that I, THEODOR HOERMANN, a citizen of Germany, residing at Brooklyn, in the county of Kings and State of New York, have invented and produced a new and original Design for Frames for Bicycle Package-Carriers, of which the following is a specification, reference being had to the accompanying drawing, which represents a perspective view of my newly-designed frame for bicycle package-carriers.

The leading feature of my design consists of a frame for bicycle package-carriers, composed of a pair of double hooks projecting from opposite ends of two pairs of converging arms and of transverse bars extending

a' b' represent a pair of double hooks projecting from opposite ends of two pairs of converging arms a b . Across each of the hooks a extend a pair of transverse bars c d . Ornamental beads c' d' may be formed at the junction of the transverse bars with the hooks.

What I claim is—

The design for a frame for bicycle package-carriers, substantially as herein shown and described.

THEODOR HOERMANN.
